UNITED STATES PATENT OFFICE.

GUSTAV LINDENTHAL, OF NEW YORK, N. Y., ASSIGNOR TO OTIS H. CUTLER,
OF SAME PLACE.

CONSTRUCTION OF TENSION MEMBERS FOR BRIDGES, &c.

SPECIFICATION forming part of Letters Patent No. 608,690, dated August 9, 1898.

Application filed June 21, 1897. Serial No. 641,647. (No model.)

To all whom it may concern:

Be it known that I, GUSTAV LINDENTHAL, a citizen of the United States, and a resident of New York, county and State of New York, 5 have invented certain new and useful Improvements in the Construction of Tension Members for Bridges and Similar Structures, of which the following is a full, clear, and exact specification, reference being had to the accompanying drawings, wherein—

Figure 1 is an elevation; Fig. 2, a cross-section on line 2 2, indicated in Fig. 1, of a wire cable and of a bearing-saddle supporting it. Fig. 3 is an elevation. Fig. 4 is a cross-section on line 4 4, indicated in Fig. 3, of a looped wire cable or eyebar with the shoe for supporting the same upon a cross-cable or bolt; and Figs. 5, 6, 7, 8, 9, 10, and 11 are cross-sections of bearing-strips used in my im- 15 proved construction of such tension members.

Similar letters of reference indicate corresponding parts in all figures of the drawings.

The shoes and saddle-bearings for wire cables are usually made to conform roughly to their outward shape. The round wires of a cable rest upon the bearing-surface only on and along the line of contact and similarly only on and along lines of contact when one wire rests upon another.

30 The well-known maxim that the bearing-surface of a constructive part must be in a certain proportion to the pressure upon the same is equally applicable to wire. When a round wire bears against a flat surface, the pressure resulting from the strain upon the wire is concentrated along the line of its contact with the bearing-surface. The same principle applies to a cable composed of a number of wires. This pressure has a tendency 35 to flatten the wire, whereby the strength of the metal may be impaired. When the wire is embedded in a close-fitting groove, the bearing-surface is greatly increased and the pressure upon the wire is distributed over a larger area, and the compression strain in the metal is diffused over a larger section.

The object of my invention is to provide ample bearing-surface for wires in wire tension members for bridges and similar structures by means of suitably-shaped strips conforming to the sectional shape, size, and

grouping of the wires of the tension member. These bearing-strips may be made of softer material than the wires and are produced by rolling or cold-drawing in suitable dies. They 55 may be made in single strips, as shown in Figs. 5, 6, 7, and 8, or in sections embracing a whole row of wires, as shown in Figs. 9, 10, and 11. Those to be used between the rows of wires are set in place during the construc- 60 tion of the wire cable. Those used between the wire cable and the shoe or saddle may be set in place upon the shoe or saddle before the winding of the coil is started, as explained in my application, Serial No. 642,678, filed 65 June 28, 1897.

Different shapes of such bearing-strips are shown in cross-section in Figs. 5, 6, 7, 8, 9, 10, and 11. Those shown in Figs. 7 and 8 are used upon the bearing-surface of a shoe or 70 saddle and the others between the rows or layers of wires. For oval or polygonal wires the bearing-strips are similarly shaped in section only, the grooves being made correspondingly to the cross-section of the wires. 75

In Fig. 1 of the drawings I have shown a section of a wire cable upon its saddle. Strips *a*, inserted between the rows of the wires *b*, are of the shape shown in Fig. 9 in section, and strips *c*, interposed between the bearing- 80 surface of the saddle *d* and the wire cable, are of the sectional shape shown in Fig. 6. For this purpose also strips of the sectional shape shown in Fig. 8 might be used, if divided into three sections, as indicated in 85 Fig. 2.

In the loop of the cable around the bearing-shoe *k* (shown in Fig. 3) the strips *e* of the sectional shape shown in Fig. 11 are used between the several rows of wire, and strips *f* of the sectional shape shown in Fig. 8 are used between the wire cable and the bearing-surface of the shoe. 90

The bearing-strips used between the rows are provided with grooves on top and bottom. 95 Those used upon the surface of the shoe or saddle have such grooves only on top, and their faces conform to the shape or surface of the shoe or saddle on which the wire cable rests. By inserting such strips between the 100 wires of a cable, a rope, or a strand its resistance against crushing pressure is greatly

increased and also its resistance against tension and bending.

I claim as my invention and desire to secure by Letters Patent—

- 5 1. Bearing-strips for cables, links, &c. composed of straight, longitudinally - arranged wires or strands, corresponding in shape and size to the shape and size of the spaces between the adjoining wires or strands of the cable, link, &c. and inserted therein to increase the bearing-surfaces of the wires or strands.
- 10 2. Bearing-strips for wire links, used in construction of bridges and similar structures, adapted to be inserted between the wire rope or cable of which the link is composed, and between the bearing-surface of its shoe or saddle, these bearing-strips having grooves corresponding in shape and size to the shape and size of the rope or wire cable and also to the shape and size of the strands comprising the rope or wire cable and having their base conformed to the shape of the bearing-surface of the shoe or saddle.

3. A wire cable or wire link composed of 25 straight, longitudinally - arranged wires or strands and of bearing-strips corresponding in shape and size to the shape and size of the spaces between the adjoining wires or strands and inserted between but not interlocking 30 with them to increase their bearing-surfaces.

4. Tension members for suspension-bridges and similar structures constructed of parallel wires and of bearing-strips, having grooves corresponding in size and shape to the size 35 and shape of the wires, inserted between the rows or strands of the wires, and also between the wire cable and the bearing-surface upon which it rests.

In witness that I claim the improvements 40 described in the foregoing specification I have signed my name in the presence of two subscribing witnesses.

GUSTAV LINDENTHAL.
